UNITED STATES PATENT OFFICE.

WILLIAM F. HOFFMANN, OF DETROIT, MICHIGAN, ASSIGNOR TO AMERICAN ELECTRICAL HEATER COMPANY, OF DETROIT, MICHIGAN, A CORPORATION OF MICHIGAN.

PLUG-SOCKET ELECTRICAL CONNECTOR.

1,072,460.

Specification of Letters Patent.

Patented Sept. 9, 1913.

Application filed October 30, 1912. Serial No. 728,645.

To all whom it may concern:

Be it known that I, WILLIAM F. HOFFMANN, a citizen of the United States of America, residing at Detroit, in the county 5 of Wayne and State of Michigan, have invented certain new and useful Improvements in Plug-Socket Electrical Connectors, of which the following is a specification, reference being had therein to the accompanying 10 drawings.

The invention relates to electrical connectors such as are employed for connecting electrically-heated sad irons and other instruments, and the invention consists in the 15 peculiar construction of the socket member for receiving the plug, and the means employed for preventing arcing between the contacts, or rattling of the plug in the socket.

In the drawings: Figure 1 is a side elevation of the connector as applied to an electrically heated sad iron, showing the plug in disengaged position. Fig. 2 is a similar view, showing the plug electrically connected. Fig. 3 is a sectional view of the guide 25 socket on line α — α Fig. 1.

A is the body of an electrically-heated sad iron; B is the handle therefor; C are the terminal contacts projecting out from the body, through insulating bushings D; E is the connector plug recessed to receive the 30 terminal C; and F is the flexible conductor attached to said plug.

To guide the plug when it is engaged with the terminal contact and to mechanically 35 support the same so as to relieve the stress from said contacts, a guide socket G is provided, which is preferably attached to the handle B as shown. This member G is preferably struck up from sheet metal, and comprises an annular portion G' and a securing 40 shank portion G². The arrangement is such that when the end of the plug is inserted in the guide socket, said plug will be properly aligned with the contact members C, so as to 45 effect the coupling by merely pressing down the plug; and in the same manner the plug may be electrically disconnected by drawing it out from the socket member.

With the construction as thus far described, there is danger that the plug may be withdrawn out of full contact with the member C while still retained in the socket G. This is objectionable for the reason that there may be arcing between the contact C

and the coöperating contacts in the plug, 55 causing an injurious burning of the same. There is a further danger that the slow withdrawal of the plug will produce the same arcing. I have therefore provided a simple construction for insuring the complete 60 mechanical detachment of the plug whenever the contacts are electrically disconnected, and for also effecting a quick breaking of the circuit to avoid arcing. This consists of a resilient member H secured to the guide 65 socket G so as to normally project laterally within the same, and in a position to intercept the plug E and to prevent it from being retained in the socket. If the plug is pressed downward with sufficient force, the 70 member H will be deflected and will lie adjacent to the side of the plug, between the same and the inner face of the socket G. In this position it exerts its tension against the plug and forms an anti-rattling device. On 75 the other hand, whenever the plug is withdrawn from the contacts C before electrical connection is broken, the lower end of said plug will be raised to a point to release the member H, and the tension of the latter in 80 returning to its normal position will effect a quick breaking of the electrical circuit, and the pushing of the plug out of mechanical engagement with the socket.

As shown, the member H is formed of 85 resilient wire, having coils H' therein, which are located in apertures I in one side of the socket G, thereby permitting the member to lie flat adjacent to one side of said socket.

What I claim as my invention is:

1. In a socket for supporting a contact plug for an electrical connection, a resilient member secured to said plug, said resilient member adapted to engage the bottom portion of the plug to eject the said plug member after the electrical connection has been broken.

2. In a socket for supporting a contact plug for electrical connection, contact members extending within said socket, a resilient member secured to the socket, said resilient member positioned above the contact member and adapted to eject the plug member after the electrical connections have been broken.

3. In a socket member for supporting a contact plug, a spring anchored at its ends to the side of the socket and the intermedi-

- ate portion of the spring member extending transversely of the socket member.
4. In a socket for supporting a contact plug for electrical connections, a spring member in said socket, said spring member secured to the socket intermediate its ends and extending transversely of the socket in its normal position and parallel with the socket when the electrical connections are coupled.
5. In a socket for supporting a contact plug for electrical connection, a spring member within said socket, said spring member adapted to eject the plug member when the contacts are uncoupled.
6. In a socket for supporting a contact for electrical connection, said socket having a spring therein, the said spring adapted to force the contact plug against the outer side of the socket when the contacts are connected and to engage the lower portion of the contact plug when the electrical connection is broken to eject the said contact plug.

In testimony whereof I affix my signature 25
in presence of two witnesses.

WILLIAM F. HOFFMANN.
